A. H. TAYLOR

RADIO RECEIVING SYSTEM

Filed Feb. 17, 1927

INVENTOR.

Albert H. Taylor,
BY Robert A. Laramée.
ATTORNEY.

UNITED STATES PATENT OFFICE.

ALBERT H. TAYLOR, OF WASHINGTON, DISTRICT OF COLUMBIA, ASSIGNEE TO WIRED RADIO, INC., OF NEW YORK, N. Y., A CORPORATION OF DELAWARE.

RADIO RECEIVING SYSTEM.

Application filed February 17, 1927. Serial No. 169,044.

My invention relates broadly to radio communication and more particularly to a system of radio reception for reducing the effects of fading of signals being received 5 from a distant transmitter.

One of the objects of my invention is to provide a circuit arrangement for signal receiving systems wherein the effects of fading of signals transmitted from a distant 10 station are substantially eliminated or reduced.

Another object of my invention is to provide a continuous wave receiving system which is arranged to compensate for the effects of fading of signaling energy from 15 a distant transmitter.

My invention will be more fully understood from the specification hereinafter following by reference to the accompanying 20 drawing which diagrammatically shows one embodiment of my invention as applied to a radio receiver system.

By my invention I provide a continuous wave receiving system wherein a plurality 25 of antennæ are coupled to independent receivers each adjusted to oscillate at different frequencies with their outputs connected to a binaural telephone circuit. As the signaling energy shifts from one frequency to 30 another the multiple receiving circuits and binaural telephone circuits follow the signaling energy compensating for the effects of fading.

Referring to the drawing, I have shown 35 separate antenna systems A_1 and A_2 , coupled to receivers R_1 and R_2 . Each receiver may contain an autodyne circuit represented at 1 and 2 adjusted to different frequencies. The autodyne circuit R_1 is constituted by 40 tube 7 having grid, filament and plate electrodes in mutually coupled circuits. Similarly, the receiving circuit R_2 is constituted by electron tube 8 included in mutually coupled circuits. Receiver R_1 is associated with 45 antenna A_1 through conductively connected circuit 9. The receiver R_2 has its input circuit coupled with the antenna A_2 through conductively coupled circuit 10.

A heterodyne 3 may be used for acting 50 upon both R_1 and R_2 but in case a heterodyne is not used and autodyne reception is resorted to, R_1 and R_2 oscillate synchronously. This they will do very readily because the receivers R_1 and R_2 are not located very 55 far apart and the reaction between the two

is such that they will hold each other in synchrony very readily when once they are approached within a few hundred cycles. This is called "pulling-in". From a percentage point of view, considering high frequency operation, when R_1 and R_2 are set only a few hundred cycles apart, they are really closely in tune. It seems that under these conditions, the oscillations will pull into step. The same operation can be obtained by using the external heterodyne 60 65 3. The output of receiver R_2 is connected to the right-hand ear phone 4 of headset 5 and the output of receiver R_1 is connected to the left-hand ear phone 6. The ear is sensitive 70 to the phase difference of the signaling energy and it manifests its sensitivity in binaural effect. In other words, the signal appears to come from a certain direction which continually shifts as the phase and intensity 75 vary.

It is found that this method can be used in the reception of stations which have small variations in frequency which can be followed on the heterodyne. This system has 80 been successfully operated at wave lengths as short as 20 meters with signals from relatively long distances, and it has been clearly demonstrated that two antennæ separated approximately one-half wave length between 85 their centers of electrical exposure give decidedly different fading. The average reception is clearly improved by using this method. It is true, that the signal appears to wander back and forth to the operator 90 due to the binaural effect, but it does not appear to be particularly annoying and during fading it commonly results that when the signal goes down in one ear, it goes up in the other, thus permitting the operator to 95 continue making copy.

While I have described my invention in one of its preferred embodiments, I desire that it be understood, that modifications may be made and that no limitations upon my 100 invention are intended other than are imposed by the scope of the appended claims.

What I claim as new and desire to secure by Letters Patent of the United States is as follows:

1. A radio receiving system comprising a plurality of radio frequency energy collecting circuits, separate radio receiving circuits coupled with said radio frequency energy collecting circuits and each adjusted to 105 110

different signaling frequencies, a circuit for generating high frequency oscillations, means for impressing said oscillations upon each of said radio receiving circuits, and a 5 divided telephone circuit comprising a pair of independent telephone receivers, one of said receivers being connected with each of said separate radio receiving circuits for responding to signaling energy over a range 10 of frequencies to which said radio receiving circuits are responsive.

2. A signal receiving system comprising a pair of independent radio frequency energy collecting circuits separate radio receiving 15 circuits connected with each of said radio frequency energy collecting circuits and tuned to respond to different frequency ranges, a system for generating high frequency oscillations coupled to each of said 20 radio receiving circuits, and a binaural telephone circuit comprising a pair of telephone receivers, one of said telephone receivers being connected with each of said receiving circuits for responding to signaling energy 25 over a band of frequencies corresponding to the total frequency range of each of said radio receiving circuits.

3. A radio receiving system comprising a pair of independent antenna circuits, a radio 30 receiving circuit coupled with each of said antenna circuits, said radio receiving circuits each being responsive to a separate range of frequencies, a generator of high frequency oscillations arranged to impress a 35 predetermined frequency upon each of said receiving circuits, a binaural telephone circuit connected with said receiving circuit comprising a pair of telephone receivers, with one of said telephone receivers inde- 40 pendently connected in each of said radio receiving circuits for indicating a response to signaling energy incident upon either of

the said antenna systems over the aggregate range of frequencies to which said radio receiving circuits are adjusted. 45

4. A radio receiving system comprising a pair of independent antenna circuits, separate receiving circuits connected with said antenna circuits and adjusted to respond to signaling energy over different frequency ranges, a binaural telephone system including a pair of independent telephone receivers with one of said telephone receivers connected with one of said receiving circuits and the other of said telephone receivers connected to the other of said receiving circuits, and a generator of high frequency oscillations arranged to act upon both of said radio receiving circuits for effecting an indication in said telephone receivers dependent upon the frequency of incoming signaling energy over a range of frequencies corresponding to the aggregate frequency range of said radio receiving circuits. 55 60

5. In a radio receiving system a pair of 65 independent antenna circuits, a radio receiving circuit coupled with each of said antenna circuits, an electron tube system connected with each of said receiving circuits and arranged to regeneratively amplify the 70 incoming signaling energy over different ranges of frequencies, a generator of high frequency energy coupled with each of said electron tube systems and a binaural telephone circuit comprising a headset having 75 separate telephone receivers with one receiver connected to one of said electron tube systems and the other receiver connected with the other of said electron tube systems for effecting an indication of the incoming 80 signaling energy independent of the effects of fading.

ALBERT H. TAYLOR.
